As examples for the bridge member Y there are mentioned:

those binding the benzene nucleus with the carbonamido group over 2 carbon atoms are preferred.

The phenylene group mentioned in the formula by

is preferably unsubstituted. It may, however, likewise be mono- or polysubstituted by halogen, lower alkyl or lower alkoxy. It may carry the remaining parts of the molecule in ortho-, meta- or para-position to each other, the para-position being preferred.

The products of the present invention may be prepared by methods well known in the benzene-sulfonyl-urea and, for example by reacting a benzene-sulfonyl-isocyanate, -carbamic acid ester, -thiol-carbamic acid ester, -carbamic acid halide or -urea substituted by the group

with a R^1 -substituted amine.

The reaction products are treated with alkaline agents, if the formation of the salts is desired.

According to the nature of the starting substances in particular of the member X one or the other method for the preparation of certain individual compounds corresponding to the general formula may be unsuitable in some cases, or, at least require measures for the protection of active groups. Such cases which do not occur very often can easily be recognized by the expert and there will be no difficulty in applying in these cases another method of synthesis.

As regards the reaction conditions, the forms of realizing the process of the invention may, in general, vary within wide limits and can be adapted to each individual case. For example, the reactions can be carried out with the use of solvents either at room temperature or at an elevated temperature.

The hypoglycemic action of the benzene-sulfonyl-urea

derivatives described above could be determined by feeding them to rabbits for example in the form of sodium salt in doses of 10 mg./kg. and determining the blood sugar value according to the known method by Hagedorn-Jensen or by means of an autoanalyzer over a prolonged period of time.

Thus we have found, for example, that 10 mg./kg. of N - [4-(β -<2-methoxy-5-methyl-benzamido>-ethyl)-benzenesulfonyl]-N'-(4,7-endomethylene - perhydro-indanyl-5)-urea provoke after 3 hours a lowering of the blood sugar of 24%. In the same manner, 10 mg. of N-[4-(β -<2-methoxy - 5 - chlorobenzamido>-ethyl)-benzenesulfonyl]-N'-(4,7 - endomethylene-perhydro-indanyl-5)-urea provoke after 6 hours a lowering of the blood sugar of 23%, whereas the known N-[4-methyl-benzenesulfonyl]-N'-butyl-urea has no blood sugar lowering effect when administered to rabbits in a dose of less than 25 mg./kg.

Furthermore, we have found that 10 mg. of N -[4-(β - β - β - β - β -methoxybenzamido)-ethyl]-benzenesulfonyl-N'- β -(4,7-endomethylene-perhydro-indanyl-5)-urea provoke after 3 hours a lowering of the blood sugar of 40%.

In the same manner 10 mg./kg. of N-[4-(β -<2-methoxy-5-chlorobenzamido>-ethyl)-benzenesulfonyl]-N'-(exo-tricyclo-[3.2.1,0^{2,4}]-octane-3-anti)-urea provoke after 3 hours a lowering of the blood sugar of 10%. After 24 hours amounts to 23% and after 48 hours still to 17%. When N-[4-(β -<2-methoxy-5-methyl-benzamido>-ethyl)-benzenesulfonyl]-N'-(spiro-<5,5>-undecyl-<3>)-urea is administered to rabbits in a dose of 0.06 mg./kg., a distinct lowering of the blood sugar can still be observed.

As regards the toxicity of the compounds the values are within the same range as those of benzenesulfonylureas, for example N-[4-methyl-benzenesulfonyl]-N'-n-butyl urea and N-[4-methyl-benzenesulfonyl]-N'-cyclohexyl-urea the LD₅₀ of which amounts to 2.5 or 4.8 grams/kg, respectively, with oral application.

Hence, the products of the present invention have a very strong blood sugar lowering action and are extra-
ordinarily well tolerated.

The benzenesulfonyl-ureas of the present invention are preferably used for the manufacture of orally administrable pharmaceutical preparations having blood sugar lowering action for the treatment of diabetes mellitus and may be used as such or in the form of their physiologically tolerable salts or in the presence of substances which cause such salt formation. For the formation of salts, there may be used, for example, alkaline agents such as alkali metal hydroxides or alkaline earth metal hydroxides or alkali metal or alkaline earth metal carbonates or bicarbonates, these agents are commonly used in the pharmaceutical industry to form physiologically tolerable salts.

The present invention, therefore, also provides pharmaceutical preparations which comprise a benzenesulfonyl-urea of the above general formula or a physiologically tolerated salt thereof, in admixture or conjunction with a pharmaceutical suitable carrier.

The pharmaceutical preparations are advantageously in the form of tablets and the pharmaceutically suitable carrier may be, for example, talc, starch, lactose, tragacanth or magnesium stearate.

65 A pharmaceutical preparation, for example a tablet or a powder, containing a benzenesulfonyl-urea of the invention or a physiologically tolerated salt thereof as the active substance, with or without one of the aforementioned carriers, is advantageously brought into a suitable unit dosage form. The dose chosen should comply with the activity of the benzenesulfonyl-urea or of the physiologically tolerated salt thereof used and the desired effect. Advantageously, the dosage per unit amounts to about 0.5 to 100 mg., preferably 2 to 10 mg., but considerably higher or lower dosage units may also be used, which, if desired, are divided or multiplied prior to their 70 administration.

The following examples illustrate the invention but they are not intended to limit it thereto:

EXAMPLE 1

N-[4-(β -<2-methoxy - 5 - chlorobenzamido>-ethyl)-benzenesulfonyl]-N'-[4,7-endomethylene - perhydro-indanyl-5]-urea

8.5 g. of N-[4-(β -<2-methoxy-5-chlorobenzamido>-ethyl)-benzenesulfonyl]-methyl-urethane (melting point 189-191° C.) were suspended in 100 ml. of xylene and after addition of 3.3 g. of 5-amino-4,7-endomethylene-perhydro-indan (boiling point: 96-98° C./8 mm.) (obtained by hydrogenation of dicyclopentadiene-bis-nitrosochloride/Raney nickel, 100° C. and hydrogen under a pressure of 100 atmospheres) dissolved in 50 ml. of xylene, the whole was heated for about 2 hours to 130° C., during which time the methanol which formed during the reaction was separated by distillation. The xylene was removed by distillation under reduced pressure, whereby the N-[4-(β -<2-methoxy - 5 - chlorobenzamido>-ethyl)-benzenesulfonyl]-N'-[4,7-endomethylene - perhydro-indanyl-5]-urea that had formed precipitated. It was recrystallized from methanol. Melting point 196-198° C.

In analogous manner there were obtained:

from N-[4-(β -<2-chlorobenzamido>-ethyl) - benzenesulfonyl]-methyl-urethane (melting point: 212-215° C.); the N-[4-(β -<4-chlorobenzamido>-ethyl)-benzenesulfonyl]-N'-[4,7-endomethylene - perhydro - indanyl-5]-urea, melting point 206-208° C. (from methanol/dioxane);

from N-[4-(β -<2-methoxybenzamido>-ethyl) - benzenesulfonyl]-methyl urethane (melting point 174-176° C.); the N-[4-(β -<2-methoxybenzamido>-ethyl)-benzenesulfonyl]-N'-[4,7-endomethylene - perhydro-indanyl-5]-urea, melting point 195-197° C. (from methanol);

from N-[4-(β -<2-methoxy-5-methylbenzamido>-ethyl)-benzenesulfonyl]-methylurethane (melting point 175-177° C.); the N-[4-(β -<2-methoxy-5-methylbenzamido>-ethyl)-benzenesulfonyl]-N'-[4,7 - endomethylene-perhydro-indanyl-5]-urea, melting point: 208-210° C. (from dilute dioxane);

from N-[4-(β -benzamido-ethyl)-benzenesulfonyl]-methyl urethane (melting point 177-179° C.); the N-[4-(β -benzamido - ethyl)-benzenesulfonyl]-N'-[4,7-endomethylene-perhydro-indanyl-5]-urea, melting point 218-220° C. (decomposition);

from N-[4-(β -<3-trifluoromethyl-benzamido>-ethyl)-benzenesulfonyl]-methylurethane (melting point 178-180° C.); the N-[4-(β -<3-trifluoromethyl-benzamido>-ethyl)-benzenesulfonyl]-N'- 4,7 - endomethylene-perhydro-indan-2-yl)-urea, melting point 175-177° C. (from methanol);

from N-[4-(β -<3-chlorobenzamido>-ethyl)-benzenesulfonyl]-methylurethane (melting point 173-175° C.); the N-[4-(β -<3-chlorobenzamido>-ethyl)-benzenesulfonyl] - N' - (4,7-endomethylene-perhydro-indan-2-yl)-urea, melting point 191-192° C. (from methanol); the N-[4-(β -<3-chlorobenzamido>-ethyl)-benzenesulfonyl]-N'-[2,6-endomethylene-cycloheptyl]-urea, melting point 186-187° C. (from methanol); the N-[4-(β -<3-chlorobenzamido>-ethyl) - benzenesulfonyl]-N'-[spiro - (2 - cyclopentane) - cyclopentyl]-urea, melting point 192-193° C.;

from N-[4-(β -<3-methoxythiophene - 2 - carbonamido>-ethyl)-benzenesulfonyl]-methylurethane (melting point 226-228° C.); the N-[4-(β -<3-methoxythiophene-2-carbonamido>-ethyl) - benzenesulfonyl] - N' - (4,7-endomethylene-perhydro-indan - 2 - yl) - urea, melting point 199-200° C. (from methanol/dimethylformamide);

from N-[4-(β -<2 - methoxy - benzamido>-ethyl)-benzenesulfonyl]-methyl-urethane (melting point 174-176° C.); the N-[4-(β -<2-methoxy-benzamido>-ethyl)-ben-

5

zenesulfonyl] - N' - 4,7-endomethylene-perhydro-indan-2-yl)-urea, melting point 187-189° C. (from methanol/dimethylformamide); the N-[4-(β -<2-methoxy-benzamido>-ethyl)-benzenesulfonyl] - N' - (2,6-endomethylene-cycloheptyl)-urea, melting point 170-172° C. (from methanol); the N-[4-(β -<2-methoxy-benzamido>-ethyl)-benzenesulfonyl] - N' - [spiro-(2-cyclopentane)-cyclopentyl]-urea, melting point 171-172° C.; from N-[4-(β -<3-methylbenzamido>-ethyl)-benzenesulfonyl]-methylurethane (melting point 200-202° C.); the N-[4-(β -<3-methylbenzamido>-ethyl)-benzenesulfonyl] - N' - (4,7-endomethylene-perhydro-indan-2-yl)-urea, melting point 175-177° C. (from methanol); from N-[4-(β -<2-methoxy-5-chloro-benzamido>-ethyl)-benzenesulfonyl]-methylurethane (melting point 189-191° C.); the N-[4-(β -<2-methoxy-5-chlorobenzamido>-ethyl)-benzenesulfonyl] - N' - (4,7-endomethylene-perhydro-indan - 2 - yl)-urea, melting point 177-179° C. (from methanol); the N-[4-(β -<2-methoxy-5-chlorobenzamido>-ethyl)-benzenesulfonyl] - N' - (2,6-endomethylene - cycloheptyl) - urea, melting point 140-142° C. (from methanol);

from N-[4-(β -<2-methoxy-5-methylbenzamido>-ethyl)-benzenesulfonyl]-methylurethane (melting point 175-177° C.); the N-[4-(β -<2-methoxy-5-methylbenzamido>-ethyl)-benzenesulfonyl] - N' - (4,7-endomethylene-perhydro-indan - 2 - yl)-urea, melting point 204-206° C. (from methanol/dimethylformamide); the N-[4-(β -<2-methoxy-5-methylbenzamido>-ethyl)-benzenesulfonyl] - N' - (2,6-endomethylene - cycloheptyl)-urea, melting point 189-191° C. (from methanol/dimethylformamide);

from N-[4-(β -<2-methoxy - 5 - bromobenzamido>-ethyl)-benzenesulfonyl]-methylurethane (melting point 197-199° C.); the N-[4-(β -<2-methoxy-5-bromobenzamido>-ethyl)-benzenesulfonyl] - N' - (4,7-endomethylene-perhydro-indan - 2 - yl)-urea, melting point 178-180° C. (from methanol); the N-[4-(β -<2-methoxy-5-bromobenzamido>-ethyl)-benzenesulfonyl] - N' - (2,6-endomethylene-cycloheptyl)-urea, melting point 170-172° C. (from methanol);

from N-[4-(β -<2-ethoxy-5-chlorobenzamido>-ethyl)-benzenesulfonyl]-methylurethane (melting point 203-205° C.); the N-[4-(β -<2-ethoxy - 5 - chlorobenzamido>-ethyl)-benzenesulfonyl] - N' - (2,6-endomethylene-cycloheptyl)-urea, melting point 172-174° C. (from methanol);

from N-[4-(β -<3,5-dimethyl-benzamido>-ethyl)-benzenesulfonyl]-methylurethane (melting point 223-225° C.); the N-[4-(β -<3,5-dimethyl-benzamido>-ethyl)-benzenesulfonyl] - N' - (4,7 - endomethylene-perhydro-indan-2-yl)-urea, melting point 190-192° C. (from methanol);

from N-[4-(β -<2-methoxy - 5 - chlorobenzamido>-ethyl)-benzenesulfonyl]-methyl-urethane: the N-[4-(β -<2-methoxy - 5 - chlorobenzamido>-ethyl)-benzenesulfonyl] - N' - [spiro - (2 - cyclobutane) - cyclopentyl]-urea, melting point 176-178° C. (from methanol/dimethylformamide/water); the N-[4-(β -<2-methoxy-5-chlorobenzamido>-ethyl)-benzenesulfonyl]-N'-[spiro-(2-cyclopropane)-cyclopentyl]-urea, melting point 167° C. (from methanol/dimethylformamide/water); the N-[4-(β -<2-methoxy-5-chlorobenzamido>-ethyl)-benzenesulfonyl] - N' - bicyclo - [5,1,0] - octyl - (8)-urea, melting point 150° C. (decomposition) (from methanol/dimethylformamide/water); the N-[4-(β -<2-methoxy - 5 - chlorobenzamido>-ethyl)-benzenesulfonyl] - N' - [spiro-(2-cyclopentane) - cyclopentyl]-urea, melting point 166-168° C.; the N-[4-(β -<2-methoxy - 5 - chlorobenzamido>-ethyl)-benzenesulfonyl]-N'-[2,5-endocyclobutylene - (1,2) - cyclohexyl]-urea, melting point 60° C.;

from N-[4-(β -<2-methoxy - 5 - methyl-benzamido>-ethyl)-benzenesulfonyl]-methyl-urethane: the N-[4-(β -<2-methoxy - 5 - methylbenzamido>-ethyl)-benzenesulfonyl] - N' - [spiro-(2-cyclopentane) - cyclopentyl]-urea, melting point 166-168° C.; the N-[4-(β -<2-methoxy - 5 - chlorobenzamido>-ethyl)-benzenesulfonyl]-N'-[2,5-endocyclobutylene - (1,2) - cyclohexyl]-urea, melting point 60° C.;

<2-methoxy - 5 - methyl-benzamido>-ethyl-benzene-sulfonyl] - N' - [spiro - (2 - cyclobutane)-cyclopentyl]-urea, melting point 174° C. (from methanol/dimethylformamide/water; the N-[4-(β -<2-methoxy-5-methyl-benzamido>-ethyl)-benzene sulfonyl] - N' - [spiro-(2-cyclopropane)-cyclopentyl]-urea, melting point 188° C. (from methanol/dimethylformamide/water); the N-[4-(β -<2-methoxy - 5 - methyl-benzamido>-ethyl)-benzenesulfonyl] - N' - [spiro - (2 - cyclopentane)-cyclopentyl]-urea, melting point 201-203° C.; from N-[4-(β -<3 - chlorobenzamido>-ethyl)-benzene sulfonyl]-methyl-urethane; the N-[4-(β -<3-chlorobenzamido>-ethyl)-benzenesulfonyl] - N' - [spiro-<2-cyclobutane>-cyclopentyl]-urea, melting point 192° C. (from methanol/dimethylformamide/water); the N-[4-(β -<3 - chlorobenzamido>-ethyl)-benzenesulfonyl]-N' - [spiro-<2-cyclopropane>-cyclopentyl]-urea, melting point 187° C. (from methanol/dimethylformamide/water); from N-[4-(β -<2-methoxy-benzamido>-ethyl)-benzenesulfonyl]-methyl-urethane: the N-[4-(β -<2-methoxy - benzamido>-ethyl)-benzenesulfonyl] - N' - [spiro - (2 - cyclopropane)-cyclopentyl]-urea, melting point 165° C. (from methanol/water); from N-[4-(β -<2-methoxy - 5 - chlorobenzamido>-ethyl)-benzenesulfonyl]-methyl-urethane: the N-[4-(β -<2-methoxy - 5 - chlorobenzamido>-ethyl)-benzenesulfonyl]-methyl-urethane; the N-[4-(β -<2-methoxy-5-chlorobenzamido>-ethyl)-benzenesulfonyl] - N' - (bicyclo-[3,1,0]-hexyl-(6))-urea, melting point 175-177° C. (from methanol); from N-[4-(β -<3-chlorobenzamido>-ethyl)-benzenesulfonyl]-methyl-urethane, (melting point 173-175° C.); the N-[4-(β -<3 - chlorobenzamido>-ethyl)-benzenesulfonyl]-N' - (spiro-<5,5>-undecyl - <3>)-urea, melting point 211-212° C. (from methanol/dimethylformamide); from N-[4-(β -<3-methoxythiophene-2 - carbonamido>-ethyl)-benzenesulfonyl]-methylurethane (melting point 226-228° C.); the N-[4-(β -<3 - methoxythiophene - 2-carbonamido>-ethyl)-benzenesulfonyl] - N' - (spiro-<5,5>-undecyl-<3>)-urea, melting point 182-183° C. (from methanol); from N-[4-(β -<2-methoxy-5-methylbenzamido>-ethyl)-benzenesulfonyl]-methylurethane (melting point 175-177° C.); the N-[4-(β -<2-methoxy - 5 - methylbenzamido>-ethyl)-benzenesulfonyl]-N' - (spiro - <5,5>-undecyl - <3>)-urea (melting point 172-173° C.) (from methanol); from N-[4-(β -<2 - methoxy - 5 - bromobenzamido>-ethyl)-benzenesulfonyl]-methylurethane (melting point 197-199° C.); the N-[4-(β -<2-methoxy - 5 - bromobenzamido>-ethyl)-benzenesulfonyl] - N' - (spiro-<5,5>-undecyl-<3>)-urea, melting point 194-196° (from methanol/dimethylformamide); from N-[4-(β -<2 - phenoxybenzamido>-ethyl)-benzenesulfonyl]-methyl - urethane (melting point 167-169° C.); the N-[4-(β -<2 - phenoxybenzamido>-ethyl)-benzenesulfonyl]-N' - (spiro-<5,5>-undecyl - <3>)-urea, melting point 166-167° C. (from methanol); from N-[4-(β -<2-methoxy-4-chlorobenzamido>-ethyl)-benzenesulfonyl]-methylurethane melting point 178-180° C.); the N-[4-(β -<2 - methoxy - 4 - chlorobenzamido>-ethyl)-benzenesulfonyl]-N' - (spiro - <5,5>-undecyl-<3>)-urea, melting point 213-215° C. (from methanol/dimethylformamide);

In analogous manner, there were obtained:

N-[4-(β -2-methoxy-5-chloro-benzamido-ethyl) - benzene-sulfonyl-N' - [spiro - (2 - cyclohexane) - cyclopentyl]-urea, melting point 152-153° C.; N-[4-(β -2-methoxy-5-methyl-benzamido-ethyl) - benzene-sulfonyl-N' - [spiro - (2 - cyclohexane) - cyclopentyl]-urea, melting point 198-199° C.;

N-[4-(β -2-methoxy-benzamido-ethyl) - benzenesulfonyl]-N' - [spiro-(2-cyclohexane)-cyclopentyl]-urea, melting point 188-189° C.; N-[4-(β -3-chloro-benzamido-ethyl) - benzene - sulfonyl]-N' - [spiro-(2-cyclohexane)-cyclopentyl]-urea, melting point 188-190° C.

EXAMPLE 2

N-[4-(β -<2-methoxy - 5 - chlorobenzamido>-ethyl)-benzenesulfonyl]-N'-(4,7 - endomethylene - perhydro-indanyl-5)-urea

A mixture of 10.3 g. of N-[4-(β -<2-methoxy-5-chlorobenzamido>-ethyl)-benzenesulfonyl]-urea, 300 ml. of toluene, 30 ml. of glycol-monomethyl ether, 1.65 g. of glacial acetic acid and 4.2 g. of 4,7 - endomethylene-perhydro-indanyl-5-amine was heated for 5 hours under reflux. The whole was then concentrated under reduced pressure the residue was treated with alcohol and the crystals obtained, constituting the N-[4-(β -<2-methoxy-5-chlorobenzamido>-ethyl)-benzenesulfonyl]-N' - (4,7-endomethylene-perhydro-indanyl-5)-urea, were recrystallized from methanol. Melting point 196-198° C.

In analogous manner, there were obtained:

the N-[4-(β -<2-methoxy-5 - chlorobenzamido>-ethyl)-benzenesulfonyl]-N'-bicyclo-(6,1,0)-nonyl - (9) - urea, melting point 110° C. (from methanol/dimethylformamide/water),

the N-[4-(β -<2-methoxy-5-chlorobenzamido>-ethyl)-benzenesulfonyl]-N'-(spiro-<5,5>-undecyl - <3>)-urea, melting point 190° C. (from methanol) and from the N-[4-(β -<2-methoxy-benzamido>-ethyl)-benzenesulfonyl]-urea, (melting point 183-185° C.); the N-[4-(β -<2-methoxy-benzamido>-ethyl)-benzenesulfonyl]-N'-(spiro-<5,5>-undecyl - <3>)-urea, melting point 207-209° C. (from methanol/dimethylformamide).

EXAMPLE 3

N-[4-(β -<2-methoxy - 5 - chlorobenzamido>-ethyl)-benzenesulfonyl]-N'-(4,7 - endomethylene - perhydro-indanyl-5)-urea

8.2 g. of N-[4-(β -acetamidoethyl) - benzenesulfonyl]-N'-(4,7-endomethylene-perhydro-indanyl-5) - urea were heated for 2 hours under reflux with a solution of 1.6 g. of sodium hydroxide in 30 ml. of water. The whole was allowed to cool to room temperature, combined with 20 ml. of acetone and 1.3 g. of glacial acetic acid and then, 4.1 g. of 2-methoxy-5-chlorobenzoyl chloride were added portionwise. After having stirred for 2 hours at room temperature the whole was suction-filtered, the precipitate was treated with bicarbonate solution and then dissolved and reprecipitated from dilute mixture of ammonia and hydrochloric acid. The N-[4-<2-methoxy-5-chlorobenzamido>-ethylbenzenesulfonyl]-N'-(4,7 - endomethylene-perhydro-indanyl-5) - urea thus obtained was found to melt, after recrystallization from a mixture of methanol and dimethylformamide, at 196-198° C.

EXAMPLE 4

N-[4-(β -<2-methoxy - 5 - chlorobenzamido>-ethyl)-benzenesulfonyl]-N'-(4,7-endomethylene - 6 - chloroperhydro-indanyl-5)-urea

7.8 g. of N-[4-(β -<2-methoxy-5-chlorobenzamido>-ethyl) - benzenesulfonyl] - methylurethane (melting point 189-191° C.) were suspended in 50 ml. of xylene and combined with 2.7 g. of 4,7-endomethylene - 6 - chloroperhydro-indanyl-5-amine (boiling point 134-138° C./8 mm.). The reaction mixture was heated for 2 hours to the boiling temperature, during which time the methanol that had formed during the reaction was distilled off; after removal by distillation of the xylene under reduced pressure, the residue was treated with strongly diluted sodium hydroxide solution. Undissolved matter was fil-

tered off and the filtrate was acidified. The N-[4-(β -<2-methoxy-5-chlorobenzamido>-ethyl)-benzenesulfonyl]-N'-(4,7-endomethylene-6-chloro-perhydro-indanyl-5)-urea thus formed was filtered off with suction and recrystallized from aqueous dioxane. The substance was found to melt at 189-191° C.;

In analogous manner, there were obtained:

from N-[4-(β -<3-methoxythiophene-2-carbonamido>-ethyl)-benzenesulfonyl]-methylurethane (melting point 226-228° C.): the N-[4-(β -<3-methoxythiophene-2-carbonamido>-ethyl)-benzenesulfonyl]-N'-(4,7-endomethylene-perhydro-indanyl-5)-urea, melting point 163-165° C. (from methanol);

from N-[4-(β -<5-chlorothiophene-2-carbonamido>-ethyl)-benzenesulfonyl]-methylurethane (melting point 174-176° C.): the N-[4-(β -<5-chlorothiophene-2-carbonamido>-ethyl)-benzenesulfonyl]-N'-(4,7-endomethylene-perhydro-indanyl-5)-urea, melting point (from methanol/dimethylformamide); 190-192° C.

EXAMPLE 5

N-[4-(β -<2-methoxy-5-chlorobenzamido>-ethyl)-benzenesulfonyl]-N'-(exo-tricyclo-[3,2,1,0^{2,4}]-octane-3-anti)-urea

18.5 g. of 4-(β -<2-methoxy-5-chlorobenzamido>-ethyl)-benzenesulfonamide are dissolved in 250 ml. dioxane, then 13.8 g. ground potassium carbonate are added and the whole is heated for 2 hours under reflux, while stirring. Then a solution of exo-tricyclo-[3,2,1,0^{2,4}]-octane-3-anti-isocyanate in benzene is added (obtained by thermal trans-position of the corresponding acid azide) and stirring is continued for 5½ hours at boiling temperature. The cooled solution is given into water, acidified, the precipitate is filtered off with suction, and recrystallized twice from dioxane/water. Melting point 188-190° C. (decomposition).

In analogous manner there is obtained:

N-[4-(β -<2-methoxy-benzamido>-ethyl)-benzenesulfonyl]-N'-(oxotricyclo-[3,2,1,0^{2,4}]-octane-3-anti)-urea, melting point 186-188° C.;

N-[4-(β -<2-methoxy-5-methylbenzamido>-ethyl)-benzenesulfonyl]-N'-(oxotricyclo-[3,2,1,0^{2,4}]-octane-3-anti)-urea, melting point 175-177° C. (decomposition);

N-[4-(β -<4-chloro-benzamido>-ethyl)-benzenesulfonyl]-N'-(oxo-tricyclo-[3,2,1,0^{2,4}]-octane-3-anti)-urea, melting point 202-204° C. (decomposition).

EXAMPLE 6

N-[4-(β -<2-methoxy-5-chlorobenzamido>-ethyl)-benzenesulfonyl]-N'-(4,7-endomethylene-perhydro-indanyl-5)-urea

5 g. of 4-(β -<2-methoxy-5-chlorobenzamido>-ethyl)-benzenesulfonamide were dissolved in 7 ml. of binormal sodium hydroxide solution and 50 ml. of acetone and to this solution, there were added dropwise, while stirring and at 0-5° C., 2.7 g. of 4,7-endomethylene-perhydro-indanyl-5-isocyanate. The whole was stirred for 3 hours, diluted with water and methanol, undissolved matter was filtered off and the filtrate was acidified with dilute hydrochloric acid. The N-[4-(β -<2-methoxy-5-chlorobenzamido>-ethyl)-benzenesulfonyl]-N'-(4,7-endomethylene-perhydro-indanyl-5)-urea that had precipitated was found to melt, after recrystallization from methanol, at 196-198° C.

In analogous manner, there were obtained:

from 4-(β -<3,4-dichlorobenzamido>-ethyl)-benzenesulfonamide (melting point 171-172° C.).

Furthermore, there were prepared in a manner analogous to that of Example 6:

the N-[4-(β -<2-methoxy-5-chlorobenzamido>-ethyl)-benzenesulfonyl]-N'-norcaran-7-yl-urea, melting point 158° C. (from methanol/water);

from 4-(β -<2-methoxy-5-methylbenzamido>-ethyl)-benzenesulfonamide (melting point 197° C.); the N-[4-(β -<2-methoxy-5-methylbenzamido>-ethyl)-benzenesulfonyl]-N'-norcaran-7-yl-urea, melting point 183° C. (from methanol/water);

from 4-(β -<4-chlorobenzamido>-ethyl)-benzenesulfonamide (melting point 225° C.): the N-[4-(β -<4-chlorobenzamido>-ethyl)-benzenesulfonyl]-N'-norcaran-7-yl-urea, melting point 137° C. (from methanol/water).

EXAMPLE 7

N-[4-(β -<2-methoxy-5-chlorobenzamido>-ethyl)-benzenesulfonyl]-N'-(4,7-endomethylene-perhydro-indanyl-5)-urea

1 g. of N-[4-(β -<2-methoxy-5-chlorobenzamido>-ethyl)-benzenesulfonyl]-N'-(4,7-endomethylene-perhydro-indanyl-5)-thiourea (melting point 137-139° C.) was dissolved in 100 ml. of methanol which had been combined with 10 ml. of dioxane. 1.1 g. of mercury oxide was added and the whole was stirred for three hours at 50-60° C. After removal of the mercury sulfide by filtration, the whole was concentrated under reduced pressure.

The N-[4-(β -<2-methoxy-5-chlorobenzamido>-ethyl)-benzenesulfonyl]-N'-(4,7-endomethylene-perhydro-indanyl-5)-isourea methyl ether thus obtained was suspended in 20 ml. of dioxane and 100 ml. of concentrated hydrochloric acid. The whole was heated for 10 minutes on the steam bath, poured into water, the precipitate was filtered off with suction and recrystallized from methanol.

The N-[4-(β -<2-methoxy-5-chlorobenzamido>-ethyl)-benzenesulfonyl]-N'-(4,7-endomethylene-perhydro-indanyl-5)-urea was found to melt at 196-198° C.

EXAMPLE 8

N-[4-(β -<2-methoxy-5-chlorobenzamido>-ethyl)-benzenesulfonyl]-N'-(4,7-endomethylene-perhydro-indanyl-5)-urea

1 g. of N-[4-(β -<2-methoxy-5-chlorobenzamido>-ethyl)-benzenesulfonyl]-N'-(4,7-endomethylene-perhydro-indanyl-5)-thio-urea (melting point 137-139° C.) were suspended in 20 ml. of binormal sodium hydroxide solution and combined with 5 ml. of hydrogen peroxide having a strength of 5%.

The whole was heated for 15 minutes on the steam bath, cooled and acidified. A precipitate was obtained which was filtered off with suction and washed with water. The N-[4-(β -<2-methoxy-5-chlorobenzamido>-ethyl)-benzenesulfonyl]-N'-(4,7-endomethylene-perhydro-indanyl-5)-urea thus obtained was found to melt, after recrystallization from a mixture of methanol and dioxane, at 196-198° C.

EXAMPLE 9

N-[4-(β -<3-methoxy-5-chlorothiophene-2-carbonamido>-ethyl)-benzenesulfonyl]-N'-(4,7-endomethylene-perhydro-indanyl-5)-urea

6.48 g. of N-[4-(β -<3-methoxy-5-chlorothiophene-2-carbonamido>-ethyl)-benzenesulfonyl]-methylurethane (melting point 189-191° C.) together with 2.26 g. of 5-amino-4,7-endomethylene-perhydro-indan and 300 ml. of dioxane were heated for 1 hour to the boiling temperature under reflux. After removal of the solvent by distillation under reduced pressure, the residue obtained was treated with strongly diluted ammonia, filtered and the filtrate was acidified. The precipitate obtained was filtered off with suction and recrystallized from methanol. The N-[4-(β -<3-methoxy-5-chlorothiophene-2-carbonamido>-ethyl)-benzenesulfonyl]-N'-(4,7-endomethylene-perhydro-indanyl-5)-urea thus obtained was found to melt at 181-183° C.

In analogous manner, there was obtained:

from N-[4-(β -<5-chlorothiophene-2-carbonamido>-ethyl)-benzenesulfonyl]-methylurethane (melting point

11

174-176° C.): the N - [4 - (β -<5-chloro-thiophene-2-carbonamido>-ethyl) - benzenesulfonyl] - N' - (4,7-endomethylene-perhydro-indanyl-5)-urea, melting point 190-192° C. (from methanol/water).

We claim:

1. A benzenesulfonyl-urea corresponding to the formula

5

wherein

R¹ is 2,6-endomethylene-cycloheptyl;
X is

in which

A stands for hydrogen, halogen, trifluoromethyl, phenoxy, lower alkyl or lower alkoxy both having 1-4 carbon atoms,

A¹ stands for hydrogen, halogen or lower alkyl of 1-4 carbon atoms and

Y is a saturated hydrocarbon chain of 1-3 carbon atoms or a salt thereof of a pharmaceutically acceptable base.

2. The compound of claim 1 wherein X is

3. The compound of claim 1 wherein X is

10

12

4. The compound of claim 1 wherein Y is

5. The compound of claim 1 wherein

6. The compound of claim 1 wherein X is phenyl which is substituted in 2-position by lower alkoxy.

7. The compound of claim 1 wherein X is phenyl which is substituted in 2-position by lower alkoxy and in 4- or 5-position by halogen, lower alkyl or alkoxy.

8. The compound of claim 1 wherein X is phenyl which is substituted in 2-position by methoxy and in 4- or 5-position by halogen, methyl or methoxy.

9. The compound of claim 1 wherein X is phenyl which is substituted in 2-position by methoxy and in 4- or 5-position by chlorine.

10. The compound of claim 1, wherein X is 2-methoxy-5-methyl-phenyl, Y is $-\text{CH}_2-\text{CH}_2-$ and R¹ is 2,6-endomethylene-cycloheptyl.
